UNITED STATES PATENT OFFICE

168,660

GRASS SHEARS OR SIMILAR ARTICLE

Charles E. Smith, Reading, Pa.

Application May 10, 1952, Serial No. 19,658

Term of patent 14 years

(Cl. D22—4)

To all whom it may concern:

Be it known that I, Charles E. Smith, a citizen of the United States of America, residing at Reading, in the county of Berks and State of Pennsylvania, have invented a new, original, and ornamental Design for a Grass Shears or Similar Article, of which the following is a specification, reference being had to the accompanying drawing forming part thereof.

Figure 1 is a side elevational view of a grass shears or similar article showing my new design; Fig. 2 is a top plan view thereof; and

Fig. 3 is a front elevational view thereof.

The dominant features of my new design are shown in solid lines in the drawing.

I claim:

The ornamental design for a grass shears or similar article, as shown and described.

CHARLES E. SMITH.
